B. H. JONES,
FOLDING COT BED,
APPLICATION FILED JUNE 4, 1915.

1,218,868.

Patented Mar. 13, 1917.

UNITED STATES PATENT OFFICE.

BENJAMIN H. JONES, OF ST. LOUIS, MISSOURI.

FOLDING COT-BED.

1,218,868.

Specification of Letters Patent. Patented Mar. 13, 1917.

Application filed June 4, 1915. Serial No. 32,033.

To all whom it may concern:

Be it known that I, BENJAMIN H. JONES, a citizen of the United States, and a resident of the city of St. Louis and State of Missouri, have invented a new and useful Improvement in Folding Cot-Beds, of which the following is a specification.

This invention relates to metal camp beds and metal cots for household, army or hospital use. The objects of the invention are strength, light weight, and compact form of the cot both open and closed, and non-collapsibility of the cot in the open position. The invention consists in the details of construction hereinafter described and claimed.

A preferred form of the invention is shown in the accompanying sheet of drawings, wherein the same reference characters designate like parts in the several views. In the drawings,

Figure 1 is a perspective view of a folding cot bed embodying the invention, only the frame and legs thereof being shown;

Fig. 2 is a cross-section through a portion of the frame on the line 2—2 in Fig. 1, showing the manner of attaching the wire spring or bed bottom; and

Fig. 3 is a side view, partly in section, of the lower end of a leg forming part of the invention.

Referring to the drawings, the camp bed shown therein has a jointed metal frame consisting of a middle section 11, a head end section 12 and a foot end section 13. Each section of the frame is composed of a bottom angle bar 14 and a top flat bar 15 which are spaced one over the other and are secured together at intervals by vertical ties or braces 16. The angle bar 14 is arranged with one of its flanges in the same vertical plane with the top bar 15, and the other flange is horizontal and projects inwardly along the top of the vertical flange. The inwardly projecting horizontal flange of the angle 14 is drilled with spaced holes 17 into which are hooked the ends of the helical springs 18 which support the bed bottom. Any suitable bed fabric may be used, such as wire links, woven wire, canvas, and the like, which should be stretched between the sides of the frame from end to end thereof for supporting a mattress.

The end sections are hinged to the ends

of the middle section by means of stiff knee hinges 19 which have their pivots above the top edges of the top bars 15. The hinges for the head end 12 are arranged to butt together before the head end swings down into the horizontal plane in line with the middle section 11, and thereby the head end is held at a slight upward slant in order to provide a raised head rest. The ends of the middle section are provided with angle iron legs 20, arranged in pairs at each end of the frame and connected by horizontal cross braces 21. The upper ends of the legs 20 are spaced inside of the vertical flanges of the angles 14 below the horizontal flanges and are hinged to the vertical flanges. Stiff-knee braces 22 hold the legs in open position. These stiff-knee braces are riveted to the inside of the vertical flanges of the angles 14, and to the outside of the legs, and fold into the spaces between the legs and angles in closed position of the legs.

The lower ends of the angle legs 20 are rounded by bending the flanges around to form tubes, and are fitted with round hard wood knobs 23 on their extremities. A hole is bored into one side of each knob, and the rounded end of the leg is forced into this hole. The slight springiness of the metal is sufficient to make a very tight and secure connection between the knob and leg, and one which will not loosen with the drying out or warping of the wood of the knob.

It is evident from the foregoing description that the cot frame is strong and light, that it can be folded with spring and mattress in place into one-half its length and that it incloses and protects the mattress when in folded condition, and that its round corners are not likely to injure objects with which it may come in contact. The wooden knobs on the legs protect the floor while the bed is in service, and prevent the ends of the legs when in folded condition from doing injury to neighboring objects. The position of the joints for the ends of the frame at a considerable distance above the plane of the spring results in the spring tending to hold the frame in open position and prevent it from folding up under sudden movements of the occupant as has frequently happened with cots as heretofore made.

The invention is not restricted to the exact construction shown and described, as it is evident that modifications in the shape and dimensions of the parts may be made 5 without departing from the invention.

I claim the following as my invention:

1. A folding cot having a sectional frame adapted to receive a spring and mattress, each section of said frame consisting of a 10 lower angle bar with one leg turned in and an upper flat bar spaced above said angle bar and secured thereto at intervals to stiffen said frame and inclose said mattress, said angle bar and flat bar being rigidly connect- 15 ed at their ends, and pivot joints connecting the ends of said sections.

2. A folding cot having a sectional frame adapted to receive a spring and mattress, 20 adjoining sections of said frame comprising alining bars, said bars being arranged on edge and spaced apart one above the other, the bars of each section being secured together at the ends by plates rigidly fastened to each bar, said plates projecting 25 above and beyond the ends of said upper bars, and pivots connecting the projecting portions of adjacent plates, whereby said plates stiffen said sections and permit fold-

ing of one section over the adjoining section.

3. A folding cot having a sectional frame adapted to receive a spring, each section of said frame consisting of a lower angle bar with one leg turned in and an upper flat 30 bar spaced above said angle bar and secured thereto at intervals to stiffen said frame, the ends of said sections butting against each other, pivot joints connecting said sections, said pivot joints being located above said upper flat bar, and a spring connected 35 to the inturned legs of said lower bar and operating in open position to prevent closing up of said cot.

4. A sectional folding cot consisting of a middle section supported on legs and two 40 end sections hinged to the ends of the middle section at their inner ends to fold over said middle section, a spring supported by the side members of said sections and by the outer ends of said end sections, said 45 spring being positioned below the pivot axis of said joints, whereby it tends to hold said end sections in open position.

Signed at St. Louis, Missouri, this 1st day of June, 1915.

BENJAMIN H. JONES.
